UNITED STATES PATENT OFFICE.

LEO ALMONT SPRAGUE, OF HENDERSON, NEW YORK.

PROPELLION MECHANISM.

1,352,922.

Specification of Letters Patent. Patented Sept. 14, 1920.

Application filed September 2, 1916. Serial No. 118,289.

To all whom it may concern:

Be it known that I, LEO ALMONT SPRAGUE, a citizen of the United States, and a resident of the village of Henderson, county of Jefferson, and State of New York, have invented a certain new and useful Propulsion Mechanism, of which the following is a specification.

This invention relates to submarine or submersible boats and has for its object propelling and controlling mechanism therefor which mechanism includes propellers shiftable into positions to apply the propelling force at various angles and directions to the hull of the boat which means is particularly simple in construction, is readily operable and highly efficient and durable in use.

The invention consists in the novel features and in the combinations and constructions hereinafter set forth and claimed.

In describing this invention, reference is had to the accompanying drawings in which like characters designate corresponding parts in all the views.

25 Figure 1 is a side elevation of my submarine boat.

Fig. 2 is a bow view thereof.

Fig. 3 is an enlarged fragmentary sectional view illustrating the actuating mechanism for the propellers and the means for shifting them.

Fig. 4 is an elevation looking to the left in Fig. 3, parts being omitted and the cover or cap plate for the propeller mechanism being removed.

Fig. 5 is an opposite elevation of parts seen in Fig. 4 showing the means for shifting the angle of the propeller shaft.

Fig. 6 is an end elevation of the housing 40 for the propeller actuating and controlling mechanism.

This mechanism for propelling and controlling submarine boats comprises generally, a propeller mounted on a shaft arranged with its axis in a plane extending in a general direction parallel to the longitudinal axis of the hull of the boat and shiftable into different radial positions, and means for shifting the propeller shaft into different radial positions.

In this form of my invention, there are two propellers and shafts arranged on opposite sides of the boat mounted on propeller shafts extending lengthwise of the hull and adjustable through arcs of 360°.

1 designates the hull of the boat provided

with passages opening through opposite sides thereof, the passages being here shown as confined by tubular projections 2.

3 are the side propellers the shafts of 60 which are adjustable to different radial positions.

4 is the stern propeller. 5 is the steering rudder and 6 is the tilting rudder. 7 designates the working deck of the submarine, 8 the conning tower or hatchway and pilot house. 9 are the railings. 10 are dead eyes or windows. 11 are hawse pipes. 12 is a door opening to the submarine deck.

The propellers 3 are mounted upon shafts 70 17 arranged in vertical planes which extend in a direction lengthwise of the hull on opposite sides thereof, these shafts 17 being journaled in carriers 20 rotatably mounted in the projections 2 at the ends thereof and 75 having radial bearings 24 near their peripheries and near their hubs in which the propeller shafts 17 are mounted, these shafts extending diametrically relatively to the carriers 20.

80 Suitable anti-friction bearings 16 are interposed between each of the carriers 20 and its companion projection 2. A wall or partition 23 separates the end portion of the extension 2 in which the carrier 20 is located 85 from the remainder of the interior of said part 2.

The outer side of each carrier 20 is closed by a suitable cover or cap plate 27 secured thereto in any suitable manner as by bolts 25. 90

95 Either propeller shaft is actuated by a shaft 13 connected to a motor in any suitable manner and extending into the projection 2 and through a suitable stuffing box 15 in the partition 23 to the outer side of said partition and intermeshing gears on the shafts 13, 17, the gear on the shaft 17 traveling planetarily around the gear on the shaft 13 during shifting of the carrier 20 to change the radial angle of the propeller shaft 17. As here illustrated, a bevel gear 18 is mounted on the shaft 13 and meshes with the bevel gear 19 on the contiguous propeller shaft 17. Thus the propeller shaft carrier 20 can be moved about its axis 100 to change the radial angle of the propeller shaft 17 about the axis of the driving shaft 13.

105 Each carrier 20 is rotated about the axis of the shaft 13 to change the radial angle of the propeller shaft in any suitable manner, as by a shaft 14 extending through a

- stuffing box similar to the box 15 in the partition 23 and having a spur gear 21 at its outer end meshing with an internal gear 22 provided on the carrier 20. The shaft 14 5 may be actuated in any suitable manner. Obviously upon rotation thereof the carrier 20 will be rocked about its axis and the angle of the shaft 17 varied into any number of angular radial positions.
- 10 In operation, the propellers 3 can be shifted independently of each other to different radial angles and either act alone or in coöperation with each other, to control the movement of the hull of the boat.
- 15 Thus the boat can be raised or lowered without the use of air tanks, by force of the propellers applied vertically upwardly or downwardly, at angles out of the vertical or out of the horizontal. The propellers 20 may be reversely arranged relatively to each other so that the force thereof is applied in opposite directions to cause a quick turning of the boat or one propeller can act vertically upwardly and the other downwardly causing the boat to roll for the purpose of loosening it when lying in mud on the bottom. Obviously, various other combinations of movements may be used.

What I claim is:

- 30 1. In a propulsion mechanism, the combination of a hull, and a propeller at one end of the hull, and side propellers located forward from the central part of the hull, shafts for the side propellers extending in planes which extend lengthwise of the hull, the shafts for the side propellers being shiftable in said planes into different radial

positions, means for rotating the side propeller shafts and means for shifting the shafts into different radial positions, substantially as and for the purpose described. 40

2. In a propulsion mechanism, the combination of a hull, a propeller at one end of the hull, a propeller between the ends forward of the central part of the hull, a shaft 45 for the second propeller extending in a plane which extends lengthwise of the hull, said shaft being shiftable in said plane into different radial positions, means for rotating the shaft, and means for shifting the 50 shaft into different radial positions, substantially as and for the purpose specified.

3. In a propulsion mechanism, the combination of a hull having a passage through the side thereof, a partition or head in the 55 passage, a rotatable carrier mounted in the passage at the outer side of the head, and having a gear associated therewith, a propeller shaft rotatable in the carrier and extending radially relatively thereto, a 60 driving shaft extending through the partition coaxially with the carrier, intermeshing gears mounted respectively on the driving shaft and the propeller shaft on the outside of the partition, means for rotating 65 the carrier, said means comprising a shaft journaled in the partition and having a gear at its outer end on the outer side of the partition and meshing with said gear of the carrier, and a cover at the outer end 70 of the projection inclosing the carrier, the propeller shaft and gears, substantially as and for the purpose described.

LEO ALMONT SPRAGUE.
